UNITED STATES PATENT OFFICE.

STEPHEN HAINES PLUM, 2D, OF MADISON, AND AMOS ACKLEY, OF CAMDEN, NEW JERSEY, ASSIGNEES TO AMERICAN TYPEFOUNDERS COMPANY, A CORPORATION OF NEW JERSEY.

SHEET-FEEDING MECHANISM.

Application filed September 22, 1925. Serial No. 57,857

This invention relates to improvements in automatic sheet feeding mechanism for printing presses and has particular reference to improvements in an automatic feeder of the type disclosed in the U. S. Patent No. 1,584,468 dated May 11, 1926.

This invention refers particularly to improvements in sheet guiding means used in connection with the said feeder and also to improvements for facilitating access to the platen during the operation of the press.

The said patent discloses an automatic feeder in which the paper is pneumatically separated and then conveyed by means of an oscillating feeder frame or separator carriage to a guide rack or transfer table from which the paper slides onto the platen. The guide rack is raised and lowered to permit the platen to move from open to closed position and heretofore the raising and lowering of the guide rack was accomplished by certain instrumentalities secured to the press itself. This is objectionable because it requires a great deal of work in attaching the feeder to the press, and it is, therefore, an object of this invention to provide a raising and lowering mechanism for the guide rack, which mechanism is directly a part of and operated by the feeder mechanism itself.

It has also been found that it is necessary to arrange the feeder mechanism in such a manner that it may be laid back in over the feeder and away from the platen so that access may be had thereto during the work, and this invention provides the necessary mechanism for thus manually moving the feeder frame and guide rack out of the way of the platen.

It has also been found that when a sheet slides from the guide rack and onto the platen, the front edge of the sheet may curl or buckle and slide out over the usual registering stops on the platen and otherwise not reach the proper printing position thereon. This invention provides suitable paper guiding means which are carried by the guide rack and operated to insure that the sheet is fed directly into printing position.

The invention will be more fully understood from the following specification read

in connection with the accompanying drawings in which—

Figure 1 is a diagrammatic side view of 55 so much of the feeder referred to in the said application as is necessary for an understanding of this invention.

Figure 2 is an enlarged side view of the guide rack and the paper guiding means 60 with the platen shown in sheet receiving position, parts being omitted and parts broken away.

Figure 3 is a view similar to Figure 2 but shows the parts in their upper position 65 when the platen is in printing position, this figure also shows in dotted line the position of the guide rack when it is laid back to permit access to the platen.

Figure 4 is a view of the parts shown in 70 Figure 3 looking in direction of arrow 4.

Figure 5 is a view of the opposite or right hand side of the feeder mechanism showing the means whereby the guide rack is raised and lowered. 75

Figure 6 is a detail view of parts shown in Figure 5 illustrating the guide rack in its lower position.

Figure 7 is a detail view of the mechanism which permits the feeder frame and 80 guide rack to be laid back as shown in Figure 3.

Figures 8 and 9 are detail views of certain parts shown in the preceding figures.

In the following description the parts 85 which are identical with similar parts in the said patent referred to will be numbered correspondingly for purposes of ready reference thereto. The press to which the automatic feeder is attached is of the well known Chandler & Price type of press, which is also well known in the art, so that only a brief reference thereto is necessary.

Referring to Figure 1 the reference numeral 6 denotes the platen of the press 95 shown in sheet receiving position. In front of the platen there is secured to the press frame suitable brackets 20 which support the inclined feed table 18 upon which the paper 15 is placed. The table is provided 100 with suitable brackets 68 in which is mounted the oscillating paper separating means identified by the swinging arms 75 and 76 which correspond with the same

parts in the application above referred to. The said arms support in a suitable manner the suction nozzles 53.

The feeder frame 75-76 is moved from a position in over the paper pile as in Figure 3 and Figure 5, to the position shown in Figure 1 where the suction ceases to function and the separated sheet of paper 65 is deposited on the guide rack 66 and from thence passes onto the platen 6 against the usual stops 16.

The guide rack comprises the said side frames 66 which are pivoted on a shaft 67 in the said brackets 68. The outer lower ends of the side frames are joined by a lower roll off shaft 17 and suitable paper side guides 19 may also be provided. The detailed construction of the parts above described and their operation and function is fully set forth in the patent referred to, to which reference is hereby made for a full understanding thereof. In this instance it is only necessary to refer to the part shown in Figure 5 in which 21 is a link pivoted to the feeder frame at 22. The other end of the link is operatively connected to a stud 23 carried by an arm 90 secured to a shaft 91 in a bearing 92. To the said shaft is further secured another arm 93 having a pin 94. A link 101 is detachably connected to said pin 94 and the other end of the link is connected to a bell crank lever 100 which is pivoted at 96 to a suitable part of the feeder mechanism, not shown. The instrumentalities described immediately above for swinging the feeder frame are identical with the same parts as disclosed in the said patent with the exception of the link 21.

The guide rack 66 is raised and lowered by means of a cam 25 which is pivoted on the shaft 67 and adjustably clamped to the guide rack by a bolt 26 and slot 27. The bracket 68 in Figure 5 has an extension 28 in which is pivoted at 29 a cam raising lever 30 which carries a cam roll 31. A link 32 is connected at the upper end of the cam lever 30 and the other end of the link is pivoted on the aforesaid stud 23.

As the feeder frame 75 is operated from the position shown in Figure 5 to the position shown in Figure 6 the cam lever 30 is correspondingly operated so that the cam roll 31 taking against the cam 25 raises and lowers the guide rack correspondingly. In the upper position of the guide rack shown in Figure 5, the rack rests on the roll 31 through the instrumentalities of the cam 25.

As now the cam roll 31 moves from the right to the left into the position shown in Figure 6, the guide rack will be correspondingly lowered as soon as the cam roll passes the point 33 of the cam. When the cam roll is moved from the left to the right it will be seen that it first lifts the cam and the guide rack until the roller passes below and to the

right of the cam point 33 and further movement of the cam roller will not effect the movement of the guide rack which will then have reached its uppermost position. The throw of the guide rack is adjusted by means of the bolt and slot 26, 27 aforesaid.

It will be noted that this guide rack raising and lowering mechanism is carried directly on the feed table 18 and thus is incorporated in the feeder mechanism and that it requires no special separate attachment to the press for this purpose. In the art of automatic feeders it is of the greatest importance that the press mechanism be disturbed as little as possible by adjustments requiring boring or drilling or other attaching means. The mechanisms thus described for raising and lowering the guide rack avoids such separate attaching means and is advantageously built into the feeder mechanism itself.

Referring now more particularly to Figures 2, 3 and 4 the paper guiding means referred to above comprises a plurality of guiding fingers 35 which are suitably clamped to a square shaft 36 and operated to project in over the platen as seen in Figure 1 to guide the sheet into proper position. When the platen moves down into printing position the guiding fingers must be withdrawn as in Figure 3 to permit the platen to swing down. To this end the square shaft 36 is at each end mounted in an arm 37, see also Figure 6, and the arms 37 are pivoted at 38, 39 in the guide rack frames 66. The operating means for swinging the arms 37 and the guiding fingers 35 are located on one side of the feeder mechanism as shown in Figures 2, 3 and 4. To the shaft 36 is clamped a short link 39 which is pivoted at 40 to an arm 41 pivoted on a pin 42 fixed in the guide rack frame 66. A link 43 is pivoted to the arm 37 at 48 and the other end of the link 43 is pivoted at 49 to a sliding cam 50.

The cam has a slot 51 which slides on the aforesaid fixed pin 42. The cam further carries an adjustable screw 52 adapted to abut the abutment 53 on the guide rack 66. A spring 54 tends to pull the cam 50 to the left in the drawings or rearwardly on the press. The cam 50 is further cut out as at 55 to slide over the shaft 67. The cam further carries a cam roll 56 which is adapted to run against a depending lug 57 on the feed table 18.

When the platen is in sheet receiving position as in Figures 1 and 2, and the guide rack 66 is lowered by the means above described, it will be seen that the cam 50 is moved downward, the slot 51 sliding on the pin 42, until the end of the screw 52 touches the abutment 53 and through the link 43 the guide fingers 35 are projected forwardly in over the platen as more particularly shown in Figure 1 to guide the sheet into position. When the guide rack is raised as

in Figure 3, the cam 50 is likewise swung around the shaft 67 and is moved backwards until the cam roll 56 strikes the lug 57. The result of the upward movement of 5 the guide rack and cam together with stoppage thereof by the cam roll 56 causes the cam to move on the pin 42 in such a manner that the guide fingers 35 are withdrawn and the parts assume the position shown in 10 Figure 3.

The movement of the guiding fingers in over the platen is adjusted in accordance with the length of the sheet by means of a screw 52. As shown in the drawings this 15 movement is relatively large, but may be shortened materially by screwing the screw 52 further in. It will be seen that the sheet guiding means operate automatically and in proper synchronism with the movement of 20 the feeder. The corresponding position of the feeder frame is indicated in both Figures 2 and 3, and in Figure 4 there is shown in dotted line a sheet 65 resting on the guide rack and about to pass therefrom and onto 25 the platen.

During the operation of the press it is frequently necessary to have access to the platen for purposes of adjustment or for other reasons. This, of course, requires the 30 platen to be in sheet receiving position as shown in Figure 1, when nearly all the movable parts of the feeder are projected in over the platen. In order, therefore, to gain access to the platen it is necessary to 35 move the feeder frame and guide rack upwardly out of the way and into the position indicated in dotted lines in Figure 3. It will, therefore, be obvious that in order to accomplish this result the link 21, see Figure 40 5, must be disconnected from the stud 23 or the feeder frames 75—76 cannot be laid back. The link 21 is, therefore, made detachable in the following manner, see Figures 45 8 and 9. The stud 23 is screwed into the arm 90 and carries to one side the link 32 which operates the cam lifting lever 30. To the other side the stud 23 carries loosely mounted thereon a bushing 70. The bushing has a pin 71 which plays in a cut out 50 72 in the head of the arm 90, and the bushing further has a straight lipped portion 73. The end of the link 21 is formed with a hook 74 which fits over the said bushing 70. As the stud 23 is moved in an arc on the 55 link 90, see Figures 5 and 7, the pin 71 moves in the cut out 72 to maintain the bushing in substantially the same position on the stud and in turn the bushing therefore prevents the hook 74 of the link 21 from jumping upwards or otherwise disconnecting itself from the stud.

Suitably supported under the feed table is a lifter shaft 75^a. On the left side of the press the said shaft carries a handle 65 76^a, see Figure 3, because the operator usu-

ally stands on that side. On the other end, Figures 5 and 7, the shaft carries a lever 77 provided with a pin 78 which moves in a slot 79 provided in a lifting cam 80 pivoted at 91 and which carries a roll 97 adapted to 70 be raised upwardly against the aforesaid link 21. A spring 98 pulls downward on a rod 99 in the cam lever 80 to normally pull the latter downwardly and away from the 75 link 21.

When it is desired to lay back the feeder frame 75—76 the operator turns down the handle 76 thus rotating the shaft 75^a in an anticlockwise direction in Figures 5 and 7 and through the instrumentalities of the 80 lever 77 and pin 78, the lifter cam 80 is raised until the roll 97 strikes the link 21 and lifts the latter upward until the hook 21 is clear off the bushing 70, the heel 102 of the hook being moved upwards against the straight 85 part 73 of the bushing as will be understood. The operator then moves the feeder frame in over the feed table and the link 21 automatically moves in the same direction to the left in Figure 7 and away from the stud 90 23, it being remembered that when the feeder frame is to be laid back the said stud will be in the position shown in Figure 7, hence the necessity for disconnecting the link 21. The link is again automatically connected to 95 the stud 23 by rotating the lifter shaft 75^a in the opposite direction to lower the lifter cam 80, this will cause the link 21 to fall down on top of the bushing 70, and when now the feeder frame is moved to the right 100 in Figure 7, the hook 74 will automatically slide in over the bushing 70 and drop into connected position with the stud 23.

Referring now to Figures 2 and 3, the reference numeral 103 denotes a hook lever which is pivoted on the sliding cam 50 at 104. The lever has a hook 105 and a slot 106 which fits over a pin 107 on the cam 50. The normal position of the hook lever is as shown in Figures 2 and 3 where it rests on the shaft 67 and, of course, moves with the sliding cam 50. When the guide rack is moved upward or laid back as in dotted lines in Figure 3, the pivot 104 of the hook lever is moved forward, to the right 110 in Figure 3, due to the changed position of the cam 50. As the cam is swung upward the pin 107 moves in the lever slot 106 so that the position of the lever hook 103 is not changed except that as the pivot 104 is moved to the right and lowered the lever hook automatically falls down so that its hook 105 engages behind the shaft 67 and thus serves to prevent the cam 50 from moving to the left in Figure 3, and this 115 in turn maintains the guide rack and the parts thereon in the raised laid back position. The limit of this position is fixed by the position of the cam 50 in that the cam roll 56 now lies upwardly against an auxil- 120 125 130

jary cam 109 which is suitably secured to the feed table 18. When the guide rack is to be lowered into its normal operating position, the operator lifts the hook lever 103 by taking hold of its handle 108, after which the guide rack may be lowered and the cam 50 automatically slides into its normal position as shown.

The foregoing is thought to fully explain this invention and the various features thereof. It will be seen that the cam mechanism for raising and lowering the guide rack comprises but few members and is directly operated from the feeder frame operating members. In this connection it should be explained that the bell crank lever 100, shown in Figure 5, is suitably connected and actuated from the press in the manner disclosed in the patent referred to.

It will also be noted that the sliding cam mechanism for operating the paper guide fingers 35 occupies but little space on the left hand side of the feeder mechanism. It will be understood, of course, that two or more of the guide fingers will be used across the feeder depending upon the size of the sheet to be printed.

While we have shown our invention in its preferred form, nevertheless it will be understood that I do not desire to be limited to the exact details illustrated or described otherwise than as required by the legitimate and intended scope of the appended claims.

35 We claim:

1. A feeding device for a press having a platen movable from a sheet receiving to an impression position comprising a paper feed table, a paper guide rack for guiding the paper in its passage to the platen and adjustable means on said paper feed table for lowering the said guide rack towards the platen when the latter is in sheet receiving position, and for raising said guide rack away from the platen when the latter moves into impression position.

2. A feeding device for a press having a platen movable from a sheet receiving to an impression position comprising a paper feed table, a paper guide rack for guiding the paper in its passage to the platen, a cam adjustably clamped to said paper guide rack and means on said paper feed table for operating said cam to raise and lower the said guide rack as the platen moves from sheet receiving to impression position.

3. A feeding device for a press having a platen movable from a sheet receiving to impression position comprising a paper guide rack, means for lowering and raising the same towards and away from the platen as the latter moves from the sheet receiving to impression position, paper guiding fingers supported on said guide rack and means for moving said guiding fingers away from the

guide rack and into operative position in over the platen when the latter is in sheet receiving position.

4. A feeding device for a press having a platen movable from a sheet receiving to impression position comprising a paper guide rack, means for lowering and raising the same towards and away from the platen as the latter moves from sheet receiving to impression position, paper guiding fingers supported on said guide rack and means for moving said guiding fingers away from the guide rack and into operative position in over the platen when the latter is in sheet receiving position, and for moving said fingers away from the platen and towards the said guide rack as the platen moves into impression position.

5. The combination with a platen, a paper guide rack, means for lowering and raising the same with respect to the said platen, paper guiding fingers on said guide rack and means automatically operable when said guide rack is lowered for moving the said paper guiding fingers into operative position with respect to the said platen.

6. The combination with a platen, a paper guide rack, means for lowering and raising the same with respect to the said platen, paper guiding fingers on said guide rack and means automatically operable when said guide rack is lowered for moving the said paper guiding fingers into operative position with respect to the said platen, and automatically operable when said guide rack is raised for withdrawing the said paper guiding fingers from the platen.

7. The combination with a platen, a paper guide rack, means for operating the latter towards and away from the platen, paper guiding fingers pivoted on said guide rack, a cam for operating said fingers and means for actuating said cam to move the guiding fingers towards and away from the platen as the said guide rack is operated as aforesaid.

8. The combination with a platen, a paper guide rack, means for operating the latter towards and away from the platen, paper guiding fingers pivoted on said guide rack, a cam for operating said fingers and means for actuating said cam to move the guiding fingers towards and away from the platen as the said guide rack is operated as aforesaid, and mechanism for regulating the length of movement of the said guiding fingers.

9. In a device of the character described a paper feed table, a paper separating mechanism normally movable from a position in over said table to a position away therefrom, operating means for said separating mechanism and means for rendering said operating means inactive to permit said separating mechanism to be moved manu-

ally into a position of rest in over said paper feed table.

10. In a device of the character described a paper feed table, a paper separating mechanism normally movable from a position in over said table to a position away therefrom, operating means for said separating mechanism, a link in said operating means connected to said separating mechanism and means for disconnecting said link from the said operating means to permit the said separating mechanism to be moved manually into a position of rest on said feed table.

15. 11. In a device of the character described a paper feed table, a paper separating mechanism normally movable from a position in over said table to a position away therefrom, operating means for said separating mechanism, a link in said operating means connected to said separating mechanism and means for disconnecting said link from the said operating means to permit the said separating mechanism to be moved manually into a position of rest on said feed table, and means on said link and operating mechanism for automatically reconnecting the same when said separating mechanism is moved away from the said position of rest as aforesaid.

30 12. In a device of the character described a paper feed table, a paper separating mechanism normally movable from a position in over said table to a position away therefrom, a link for operating said mechanism, actuating means for said link, a cam, a shaft for lifting said cam to disconnect

the said link from its actuating means to permit said separating mechanism to be moved manually into a position of rest on said feed table irrespective of the preceding position of said separating mechanism, means for automatically reconnecting said link and its actuating means when said separating mechanism is moved in the reverse direction and means for operating said shaft to lower the said cam to permit the automatic reconnection as aforesaid.

13. In a device of the character described, a paper guide rack, a support therefor, means for operating said guide rack into predetermined positions with respect to said support, said guide rack being adapted to be moved manually into a position of rest different from its operating positions aforesaid and means on said guide rack for automatically locking it in its said position of rest when manually moved as aforesaid.

14. In a device of the character described, a paper guide rack, a support therefor, means for operating said guide rack into predetermined positions with respect to said support, said guide rack being adapted to be moved manually into a position of rest different from its operating positions aforesaid and means on said guide rack for automatically locking it in its said position of rest when manually moved as aforesaid, said automatic locking means being adapted to be manually unlocked to release the paper guide rack from its position of rest.

AMOS ACKLEY.
S. HAINES PLUM, 2D.
